COSMOSARIUM

Robert V. Morse, Ithaca, N. Y.

Application May 15, 1936, Serial No. 79,824

15 Claims. (Cl. 35—46)

This invention relates to astronomical and terrestrial apparatus, celestial globes, terrestrial globes, planetariums and the like, and has for its object the representation of the heavenly bodies, including the earth as a planet, as viewed from a point out in space. I am aware that celestial globes have been used on which the relative positions of the stars are shown, but they have generally had the stars on the outside and have not shown the earth in space. I am also aware that terrestrial globes have been used, generally with political divisions indicated by arbitrary contrasting colors, but with no serious attempt to reproduce the earth in its natural form and color, nor to place it in a setting of the stars accurately represented. I am also aware that planetariums have been invented in which the fixed stars and planets, other than the earth, are shown by light projected on the interior of a hemisphere. The observers have been within the hemisphere and viewed the stars as they would be seen on any starlight night, as viewed from the earth, but not as viewed from space.

As distinguished from these, the present invention utilizes a hollow spherical globe or spherical dome, as distinguished from the hemispherical dome of a planetarium, and provides means for placing the observer so that he may view the interior of the dome from a point just outside the interior surface thereof, so that he may see the opposite surface but not the adjacent surface. The present invention also provides a means for placing a realistic terrestrial globe between the observer and the opposite interior surface carrying the stars, so that the earth appears to be floating in outer space against a background of the stars. It will be understood that when one is out in space beyond the earth's atmosphere, abysmal space is absolutely black, and the stars can be seen in broad daylight shining with their utmost brilliancy, when one's back is turned toward the sun.

This device is termed a cosmosarium, as distinguished from a planetarium, as it shows the entire visible cosmos or universe, including the planet Earth. The means for holding the earth in space without visible support, for representing the stars and planets, for placing the observer where he can obtain the effect, the means for illuminating the terrestrial globe as by the sun's rays without exposing the interior wall of the celestial globe beyond or obliterating the stars, the means for moving the earth and planets, and various other features, will become apparent as the description proceeds.

Referring now to the drawings,

Fig. 1 is a vertical cross-sectional view of the apparatus, the terrestrial globe being in elevation and the celestial globe in cross-section.

Fig. 2 is a detail cross-section showing an observer on the surface of the celestial globe viewing the opposite interior surface, the adjacent surface at the point through which he is looking having an opening or window.

Fig. 3 is an elevation showing the mechanism for elevating and rotating the terrestrial globe.

Fig. 4 shows one means for representing the stars, and for illuminating the terrestrial globe.

Fig. 5 shows another means employed for representing groups of stars.

Fig. 6 shows means for representing the solar system which may be substituted at times for the terrestrial globe, thus showing the whole solar system as viewed from inter-stellar space, as distinguished from interplanetary space.

Fig. 7 shows an alternative method of mounting the terrestrial globe, with its axis at an angle instead of vertical.

Fig. 8 is an elevation, partly in section, of a miniature type of cosmosarium.

Similar reference numerals refer to similar parts throughout the various views. The stars which in the apparatus actually appear as bright spots against a dark background are shown in the drawings as dark spots on a light background, due to the limitations in the reproduction of patent drawings.

Referring now to Fig. 1, a terrestrial globe 1 in natural color (disregarding atmosphere), is mounted on an elevator shaft or post 2 operated by an elevator mechanism 3, by which it may be raised to the center of the hollow celestial globe 4, whose interior is studded by the stars 5. The stars 5 in practice are carefully arranged in their true constellations, and are produced by lights 40 embedded in the globe 4, as will be more fully explained later. The terrestrial globe 1, representing the earth, is illuminated by a restricted beam or group of beams of light 7 which are directed so as to strike one side of the earth 1 but not pass beyond it. This leaves the other side of the celestial dome 4 in darkness. The principal beams 7 may come from the round spot light 8 representing the sun.

The season of the year selected for representation is preferably the late summer or harvest season in the Northern Hemisphere, about the month of August. At this time the north polar snow cap is relatively small, surrounded by the dark waters of the Arctic Ocean. Below that come

the dark green of the northern woods, passing into autumnal coloration further south; then the great fields of the agricultural regions in the color of ripened grain, with wooded areas still green.

5 The oceans are in general blue, the various oceanic currents varying in hue from the brilliant blue of the Gulf Stream for example to the somber gray-greens of the Arctic currents. In the tropics, aside from the mountains and deserts, 10 green is the predominant color, merging into browns in the cultivated and winter regions of the Southern Hemisphere. August being winter in the Southern Hemisphere brings the Antarctic polar snow cap to its maximum dimensions, with 15 the South Pole in darkness. This permits the supporting post 2, which is black, to be invisible, and thus creates the illusion that the earth 1 is floating unsupported in space.

The hollow globular shell 4 in which the stars 20 5 are carried is pierced at intervals in the dark spaces between stars by observation holes 10 as shown in Fig. 1 and more in detail in Fig. 2, these openings 10 being preferably covered with glass to exclude dust which otherwise might settle on 25 the globe 1 and gradually discolor it. In order that the observers may reach various points of vantage and view the cosmos from various angles, a spiral ramp 11 or 11' is provided. This is preferably made in double spiral or double helical 30 form, so that one ramp, as indicated for example by the dot and dash lines 11, may be used by those ascending and the other ramp indicated by the dotted lines 11' may be used by those descending. This permits a large number of 35 observers to use the apparatus without crowding or crossing each other. It overcomes one of the chief limitations of planetariums from a financial standpoint, in that they have been limited to the 40 number of people who could be seated inside of a dome, multiplied by six or eight, corresponding to the number of lectures per day. While this in the ordinary planetarium totals no more than a very small theatre, the cosmosarium can handle a much greater number, as it permits a continuous 45 flow of observers. An ordinary planetarium can also be used in conjunction with the cosmosarium if lectures are desired.

Taking up the mechanism more in detail, the earth 1 may be lowered as well as raised by the 50 elevator mechanism 3 operating the post or plunger 2, and this permits the earth 1 to be brought down to the level of the lower portion of the celestial globe 4 for cleaning or repair. In Fig. 3 the earth 1 is shown in its lowered position. 55 The elevating mechanism 3 is preferably of the hydraulic type, commonly used in various forms of lifts and passenger elevators, consisting in general of a rod or plunger 2 which is raised or lowered by hydraulic pressure operated by a suitable control mechanism 14, the details of which are well known in the art. Any other suitable type of elevating mechanism may be used, either mechanical or hydraulic or the terrestrial globe 1 may be suspended from above by a wire or 60 cable if desired.

In addition to the elevating or supporting device, means 15 are provided to slowly rotate the globe 1 on its axis, as shown in Fig. 1 and on a larger scale in Fig. 3. This globe rotating means 65 70 15 consists of a worm wheel 16 secured to the rod or shaft 2 by means of the clamp 17. The worm wheel is rotated slowly by the worm 18 driven by the motor 19 or other suitable power means. The shaft 2 is secured to and supports 75 the globe 1, so that when the apparatus is oper-

ated the earth appears to be slowly rotated. A good speed is about one rotation in two or three minutes, or faster for smaller apparatus.

When the globe 1 is being raised or lowered, which only happens at comparatively long intervals, the clamp 17 is loosened, thus permitting the shaft 2 to slide longitudinally through it, without disturbing the worm wheel 16 and worm drive mechanism 18 and 19. The opening at the bottom of the celestial globe may be closed if desired by a removable screen S, on which the southernmost stars may be represented. This can be removed when the earth is lowered.

Referring now to Fig. 4 and Fig. 5, these show more in detail means for showing the stars 5 on the interior wall of the celestial globe 4, which is spaced from and surrounds the terrestrial globe or earth 1. The brighter stars and planets may be represented by individual electric lights 22 sufficiently sunk in the wall 4 and provided with 20 lenses 23 so that the light is not diffused in the interior of the dome 4,—which might illuminate it too greatly and expose its structure,—but instead the light of the stars is restricted and chiefly directed or spotted on the earth. The stars can 25 still be seen at angles beyond the perimeter of the earth 1, just as an automobile headlight can be seen at lateral angles even though the beam is directed forward; but the major portion of the illumination, so far as revealing or exposing any- 30 thing, remains in the path of the beam. Various principal stars, used as individual spot lights with directed beams, may have their beams blended on the surface of the earth 1 so as to simulate or assist the representation of daylight on one 35 side of the earth 1, and moonlight on the other side of the earth 1. The intensity of the various stars or spot lights may be adjusted to give the desired degrees of illumination at various regions on the earth 1.

The principal illumination of the earth 1 may come from a large spot-light 8 representing the sun, as previously described in connection with Fig. 1. The beams from this sun 8 are restricted as indicated by the dotted lines 7 in Fig. 1, so as to be intercepted by the earth 1 and not strike the opposite wall sufficiently to expose its construction. The large spot-light or sun 8 may be used alone or in conjunction with the small spot-lights 22 described, or the sun 8 can be omitted 50 and the lights 22 depended upon entirely. Where the large light or sun 8 is used reflecting elements 30, preferably of the jeweled or prismatic type, may be used for the stars. These reflecting elements 30 may be used in any case to 55 represent the minor stars, and in fine form to represent the milky way and other star clouds.

In the simplest form the planets may be placed at certain fixed positions, like the fixed stars, indicating the relative positions of the planets at a 60 certain time. If the progress of the planets through the heavens is to be shown, a string of additional sockets may be used, and the light turned on successively from one to another, so as to show the changing position, without moving 65 parts other than the switch, after the manner of advertising signs.

If a fairly rapid and smooth motion of the planets is desired, the planets 34 may be arranged on tracks 35 laid on the interior surface of the 70 celestial globe 4 as shown in Fig. 2, and provided with little motors or carrier mechanisms 36, such as are used in the toy train and department store change carrier arts for example, by which the light or lights corresponding to the planet may be 75

made to move at any desired rate. The same may be used to represent an occasional comet, and the moon. It will be understood that, unlike an ordinary planetarium, it is not necessary or proper 5 that all the stars of the celestial globe of the cosmosarium should rotate or appear to move in the heavens. Except for the relatively few planets, and the moon, all the other stars are fixed stars, and so may be fixed in the celestial 10 globe 4. In the ordinary planetarium it is necessary to move all the stars, because they are seen as viewed from the earth's surface, and are therefore given the appearance of motion by the rotation of the earth; though in reality it is well 15 known that the stars remain still while the earth turns.

In the present invention the elaborate mechanism heretofore required to move all the stars is dispensed with, by reason of the concept of 20 placing the observer at a detached point in outer space, from which it is apparent that the stars, generally speaking, are fixed, and it is the earth that turns.

Where it is desired to represent a number of 25 stars 5 by a single light 22', a transparency 48 may be employed as shown in Fig. 5. This simplifies construction and servicing, and is applicable to some groups and constellations.

The observation ports 10 have different angles 30 of view depending on their position in the celestial globe 4, and as previously stated the ports 10 are located at dark spaces between the stars 5; or conversely, the stars 5 may be described as spaced between or around the ports 10. Slight displacements in the positions of some of the stars can 35 be tolerated without spoiling the effect. At the top of the celestial globe 4 the windows or ports become horizontal, as shown in Fig. 6, so that the observer may look down on the earth 1, through the port or window 10.

As an occasional feature the earth 1 may be lowered to the bottom of the celestial globe 4 as shown in Fig. 3, so that it is no longer visible, and the sun spot-light 8 may be turned off.

45 Then from the top of the celestial globe 4 a model of the solar system 45 (conventionally shown in the drawings) may be lowered by means of the cables 46 and drums 47 to the central portion of the globe 4 formerly occupied by the earth 1.

50 This model 45 may then be illuminated and operated in any of the well known manners customary to such models, and provides a representation of the solar system as viewed from many millions of miles out in interstellar space, yet from a point 55 relatively close to the solar system as compared to distances of the fixed stars. It is permissible to modify the true scale sizes and distances of the sun and planets, in order that they may be conveniently seen, as is customary with models 60 of the solar system.

In Fig. 1 the shaft or axis 2 of the terrestrial globe or earth 1 has been shown in the vertical position, in which case the beam 7 of the sun 8 will come down at an angle from above, if the 65 time selected for representation is summer in the Northern Hemisphere. This vertical manner of mounting the axis of the earth 1 is preferred by me, but I do not wish to be understood as indicating that the present invention is limited there- 70 to, as the axis of the earth as shown in Fig. 7 may be inclined in the ordinary manner common to terrestrial globes, or at any desired angle, the only difference being that the sun's rays 7 from the spot-light 8' then come horizontally or at 75 some other angle, and the stars would also be

shifted accordingly, with the North Star coming at the position indicated by a projection of the axis 2' of the earth 1.

I am aware that it is customary to represent the axis of the earth as tilted to the plane of the table or base upon which an ordinary terrestrial globe rests. This shows the inclination of the earth's axis to the plane of the earth's orbit around the sun, and is useful in demonstrating the cause of the change of seasons. While this 10 in conventional thought leads to the belief that the axis in the present invention must be tilted in order to truly represent reality, it will be seen on further consideration that there is no fixed reference plane, such as a table, in space, but 15 that all positions are relative. It is, for example, a purely arbitrary convention which places the north pole of the ordinary terrestrial globe on top; the globe would in all respects be just as true if the south pole were placed at the top. 20 So in the present invention, whether the axis is vertical or at an angle, becomes merely a question of whether we chose as our reference plane the plane of the earth's rotation on its own axis or the plane of the earth's orbit around the sun. 25 It is therefore just as proper to select the earth on which we stand as the basis as it is to select the path around the sun in which the earth also moves, the latter being relatively intangible, and as abstraction of which human beings are less 30 conscious. In either case, from the standpoint of the universe, the selection is arbitrary; and if the pivot 2 is placed vertically, as shown in Fig. 1, the load is better supported, and the shaft 2 not subjected to bending stresses. However, if concessions must be made to conventional habits of 35 thought, the inclined position as shown in Fig. 7 is equally proper.

The cosmosarium apparatus above described may be enclosed or housed in any structure of 40 suitable architectural design,—the architectural design being immaterial so far as this invention is concerned. However, if it is not protected from the weather, by being surrounded by some much larger structure, or by a natural shelter such as 45 a cave, it is generally desirable to have an outer spherical shell 50 to protect the device and also to maintain the observation ports 10 in relative darkness, so that the observer's eyes will be adjusted to the relatively dim illumination of the 50 earth 1 by artificial light. The outer shell 50 may have small ports or windows 51 to admit a moderate amount of light.

The apparatus may also be built in much 55 smaller form, including the miniature type shown in Fig. 8, suitable for household use, or schools. In this form the outer shell 50 and ramps 11 and 11' as shown in Fig. 1 are omitted, and the observer places his eye to peep-holes 55 in the shell of the celestial globe 4. The earth 1 may be 60 illuminated by a beam of light as has been described, or can be made of transparent material and illuminated from an interior light placed inside the terrestrial globe 1, which can be provided with a suitable shade so that one half of the 65 earth 1 appears in darkness or only dimly illuminated, while the other half appears to be illuminated as in daylight. An interior light in a transparent terrestrial globe of the conventional political type, showing countries in arbitrary 70 colors, is well known in the art, so the details of the interior light, with its shade and mounting, need not be further described. Similar interior lighting might be used on the larger globe 1 of Fig. 1, but due to the difficulty of making so large 75

a globe of transparent material, the external beam 7 of Fig. 1 is generally preferred.

In the miniature form such as in Fig. 8, the stars may be represented in various ways, according to expense permitted, ranging from pin holes 65 in the shell 4, to reflecting materials, as have been described, placed on the interior of the shell, used solely or in conjunction with the pin holes, or electric lights illuminating holes or transparent cies. It is also possible to construct the shell 4 of glass, coated as in a transparency, leaving transparent holes for the stars, to which the eye may be placed to view the interior. Such a device forms a novel and beautiful celestial globe, with 15 or without the earth 1 inside.

The term "celestial globe" as used herein does not necessarily mean that it must be a perfect or completely spherical globe or body, it being generally understood in the art that such globes usually have a base, or sometimes openings or passages for access to the interior, or other such minor modifications in form, while substantially retaining the effect of a globe or sphere on which the stars are mounted. Such an opening for example may be closed by the screen S as described.

It is believed that a terrestrial globe in natural form and color, is of itself a novel and useful article of manufacture for educational purposes, whether associated with the stars or not. The 30 ordinary terrestrial globes are designed to emphasize political features, such as geographical names and the boundaries of countries, generally shown in arbitrary contrasting colors. The student then does not visualize the great natural features of the earth as they are,—such as the snow caps, mountains, deserts, forest and fields, and the student therefore loses the opportunity to learn natural facts in the most effective manner,—namely, by direct observation; he is unduly impressed with political and national divisions. It is believed that a terrestrial globe under the present invention, where a serious attempt is made to represent in their actual form and color the natural features of the earth's surface, so that they are visible and recognizable in themselves, is of educational value in arousing the interest of the student in the geography of the earth as man's abode, with a broader point of view than nationalism. I am aware that there have been crude representations of the earth, with the sea blue and the continents green, generally used for advertising purposes; but as these colors are incorrect, and do not bring out the various natural features above-mentioned, they neither in purpose nor result attain the effect of the present invention. So far as I am aware, the concept of a terrestrial globe having its actual geographic features represented realistically in natural colors is new in the art, and creates a useful educational device.

60 While I have in the foregoing described certain specific examples, it will be understood that they are merely for purposes of illustration, to make clear the principles of the invention, which is not limited to the particular forms shown, but is susceptible of various modifications and adaptations in different installations, as will be apparent to those skilled in the art, without departing from the scope of the invention as stated in the following claims. In these claims the word "astronomical" is to be understood as used in its broadest sense, to cover the terrestrial as well as the celestial, the earth being considered as coming under astronomy, as it is one of the planets.

I claim:

75 1. In astronomical apparatus, the combination

of a hollow celestial globe having a darkened opaque inside surface and having lighted stars represented on said darkened opaque inside surface, a terrestrial globe inside said celestial globe, and means by which an observer located closely adjacent the celestial globe on the outside of the surface on which the stars are shown may look through between adjacent stars and see the stars on the opposite interior wall of the celestial globe and simultaneously see the terrestrial globe 10 against a dark background, whereby the earth may be represented against the blackness of abysmal space.

2. In astronomical apparatus, the combination of a hollow celestial globe having a darkened inside surface and dotted with stars having lighted representations of the stars on said darkened inside surface, and window openings located in the dark spaces between stars, whereby an observer may see the stars on the opposite interior 15 surface without seeing the surface adjacent to him.

3. In astronomical apparatus, the combination of a hollow celestial globe having a darkened interior surface and having lighted representations of the stars on said darkened interior surface and viewing means extending through the wall of said globe, whereby an observer may see the opposite interior side of the globe without seeing the exterior side of the globe adjacent to him, said viewing means being located in the dark spaces between stars.

4. In astronomical apparatus, the combination of a hollow celestial globe having a wall of opaque material, said wall having viewing apertures so 35 that the interior may be viewed from the outside, and means for illuminating representations of the stars on the inside surface of said wall, so that they may be seen in the darkness of the interior, said viewing apertures being located between star 40 representations in the region of the heavens depicted by the stars.

5. In astronomical apparatus, a celestial globe having illuminated stars represented on its interior surface, and numerous small windows scattered at intervals among the stars, the total light 45 from said windows being so small that the interior of the globe is left in relative darkness so that the stars may be seen as at night, when viewed through said windows.

6. In astronomical apparatus, the combination of a hollow celestial globe having a darkened inside surface and having lighted stars represented on said darkened inside surface, a terrestrial globe inside said celestial globe, and means by which an observer located closely adjacent the celestial globe on the outside of the surface on which the stars are shown may look through between adjacent stars and see the stars on the opposite interior wall of the celestial globe and simultaneously see the terrestrial globe against a dark background, whereby the earth may be represented against the blackness of abysmal space, and means for elevating and lowering the terrestrial globe, so that it can be located substantially 60 in the center of the celestial globe and occasionally lowered to the bottom of the celestial globe.

7. In astronomical apparatus, the combination of a hollow celestial globe having a darkened inside surface and having lighted stars represented on said darkened inside surface, a terrestrial globe inside said celestial globe, and means by which an observer located closely adjacent the celestial globe on the outside of the surface on which the stars are shown may look 70 75

- through between adjacent stars and see the stars on the opposite interior wall of the celestial globe and simultaneously see the terrestrial globe against a dark background, whereby the earth
- 5 may be represented against the blackness of abysmal space, means for holding the terrestrial globe substantially in the center of the celestial globe, and means for rotating the terrestrial globe.
8. In astronomical apparatus, the combination
- 10 of a hollow celestial globe having a darkened inside surface and having stars represented on said darkened inside surface, a terrestrial globe inside said celestial globe, and means by which an observer located closely adjacent the celestial
- 15 globe on the outside of the surface on which the stars are shown may look through between adjacent stars and see the stars on the opposite interior wall of the celestial globe and simultaneously see the terrestrial globe, means for holding
- 20 the terrestrial globe substantially in the center of the celestial globe, means for rotating the terrestrial globe, and means for illuminating one side of the terrestrial globe, said illuminating means being restricted to one side of the ter-
- 25 restrial globe whereby not to illuminate the means for holding the terrestrial globe in place nor the interior details of the celestial globe, so that the earth is represented as floating unsupported in abysmal space.
- 30 9. In astronomical apparatus, a hollow celestial globe having representations of the stars on the interior surface thereof and viewing means extending through the wall of said globe, whereby an observer may see the opposite interior side of
- 35 the globe without seeing the exterior side of the globe adjacent to him, and spiral means by which observers may pass surrounding the wall of said celestial globe, and connecting the various points of view, so that an observer may see the
- 40 interior from different angles and elevations as he progresses around said spiral.
10. In astronomical apparatus, the combination of a hollow celestial globe having lighted stars represented on the darkened opaque inside sur-
- 45 face thereof, a terrestrial globe inside said celestrial globe, and means by which an observer located closely adjacent the celestial globe on the outside of the surface on which the stars are shown may look through between adjacent stars
- 50 and see the stars on the opposite interior wall of the celestial globe and simultaneously see the terrestrial globe, whereby the earth may be represented in space, and means for representing the planets in various positions on said celestial globe,
- 55 while the positions of the stars remain stationary.
11. In astronomical apparatus, the combination of a terrestrial globe representing the earth with its natural features represented in realistic form and natural surface coloration, a celestial
- 60 globe surrounding said terrestrial globe, the interior of said celestial globe being in darkness except for lights representing the heavenly bodies, means for supporting the terrestrial globe in a substantially invisible manner when viewed
- 65 against the lights of the stars, a series of viewing means arranged spirally around and outside the celestial globe and located in dark spaces between stars, whereby the earth may be seen as viewed from space from different positions.
12. In astronomical apparatus, the combination of a terrestrial globe representing the earth with its natural features represented in realistic form and natural surface coloration, a celestial globe surrounding said terrestrial globe, the interior of said celestial globe being in darkness except for lights representing the heavenly bodies, means for supporting the terrestrial globe in a substantially invisible manner when viewed against the lights of the stars, a series of viewing
- 10 means arranged spirally around and outside the celestial globe and located in dark spaces between stars, whereby the earth may be seen as viewed from space from different positions,
- 15 and means for rotating the earth.
13. In astronomical apparatus, the combination of a terrestrial globe representing the earth with its natural features represented in realistic form and natural surface coloration, a celestial globe surrounding said terrestrial globe, the interior of said celestial globe being in darkness except for lights representing the heavenly bodies, means for supporting the terrestrial globe in a substantially invisible manner when viewed against the lights of the stars, a series of view-
- 20 ing means arranged spirally around and outside the celestial globe and located in dark spaces between stars, whereby the earth may be seen as viewed from space from different positions,
- 25 and means for representing the planets in various positions relative to the fixed stars.
14. In astronomical apparatus, the combination of a celestial globe, a terrestrial globe inside of said celestial globe, means for supporting said terrestrial globe, spotlights arranged in said celestial globe to represent some of the heavenly bodies, said spotlights being directed upon the surface of the earth so as to be intercepted thereby and not reveal the details of the opposite interior of the celestial globe or of the supporting means of the terrestrial globe, whereby the earth is represented as floating in space.
- 30
15. In astronomical apparatus, the combination of a terrestrial globe representing the earth with its natural surface coloration so as to indicate realistically mountains, snow-caps, forests, fields, deserts, and bodies of water, a celestial globe surrounding said terrestrial globe and having stars represented on its internal surface, means for movably supporting the terrestrial globe within the celestial globe, means for illuminating one side of the terrestrial globe, said illuminating means being located and directed to shine on one side of the globe but not on said supporting means, which is located in the shadow cast by the globe and in a relatively unilluminated region, so that the globe appears to float in space, windows in the wall of the celestial globe located at intervals between the stars, whereby the earth may be viewed as in space surrounded by the stars, an external wall surrounding the
- 35 celestial globe, and spiral passage ways located between the celestial globe and said external wall whereby observers may pass from one window to the next and view the representation of the earth
- 40 in space from various angles and elevations.
- 45
